UNITED STATES PATENT OFFICE

JAMES F. MULLEN, JR., OF CHICAGO, ILLINOIS

RAIL CLEANER

Application filed May 21, 1930. Serial No. 454,224.

This invention relates to devices for cleaning snow and ice and other things off the rails or other electrical conductors of electrically-operated railways.

Generally stated, the object of the invention is to provide novel and improved means for effectively removing the snow or ice or other deposits from the third rail of an electric railway, or from any other electrical conductor, from which the cars derive current for the operation of the motors thereof, thereby to insure effective contact between the said third rail or other electrical conductor and the shoe or other engaging element of said cars.

To the foregoing and other useful ends, the invention consists in the matters herein-after set forth and claimed, and shown in the accompanying drawing, in which,—

Fig. 1 is a side elevation of the truck portion of an electrically-operated street railroad car, showing a device for removing the snow or ice, or other things, from the third rail of the system embodying the principles of the invention.

Fig. 2 is an enlarged side elevation of said device, showing certain portions thereof in vertical section.

Fig. 3 is a plan view of the device shown in Fig. 2 of the drawing, with certain portions broken away for convenience of illustration.

As thus illustrated, the invention comprises a bracket 1 pivoted at 2 on a bracket plate 3, which latter is suitably secured to the truck 4 of the car. An electric motor 5 is suitably mounted upon said bracket 1, and a vertical tube 6 is screwed into the lower portion of said bracket 1, as shown. A shaft 7 is disposed vertically in said tube, in position to slide up and down therein, being provided with a fixed shoulder portion 8, as shown. A coil spring 9 is interposed between the portion 8 and the lower side of the motor 5, tending to press the shaft downward. The lower end of the tube 6 is provided with a screw-threaded cap 10, as shown, whereby, if desired, the tube 6 can be filled with a lubricant.

A horizontal disk or cutter wheel 11 is suitably secured to the lower portion of the shaft

7, in position to rest flatwise upon the top of the third rail 12 of the railway system. This rail 12, of course, is the source of power for driving the motor car, and for changing the motor 5, very obviously. This disk 11 is 55 preferably provided with peripheral teeth 13 for cutting the snow or ice, or other deposits, away from the top of said rail.

A coil spring 14 is preferably interposed between the bracket 1 and the bracket plate 60 3, below the pivot 2, this spring tending to tilt the motor and cutter into the position shown in dotted lines at 15 in Fig. 1. Said spring is mounted on a stop 16 between the bracket 1 and the plate 3, which stop limits 65 the rearward tilting motion of the motor tilting device, whereby in operation the motor and cutting device assume the position shown in full lines in Figs. 1 and 2 of the drawing.

However, as soon as the cutting device or 70 cleaning device, thus shown and described, is brought over the gap 17 in the third rail, the said device then assumes the position shown in dotted lines at 15 so that it may ride up the incline at the side of the gap which it 75 is approaching, and then swung down into vertical position, as shown, the cutter 11 moving upwardly against the pressure of the spring 9 in a manner that will be readily understood.

Thus, the shoe or contact member 18 of the car travels on the third rail 12, directly behind the cutting and cleaning device 11, and any snow or ice on the rail, or even other deposits, will be cut away directly in front 85 of said shoe, whereby the latter will have contact with the scraped or cleaned top of the rail, it being understood that the motor 5 rotates the shaft 7 and the cutter 11 in the direction indicated by the arrow in Fig. 3 of 90 the drawings. The electric motor car, of course, will travel in the direction indicated by the arrow in Fig. 1 of the drawing.

What I claim as my invention is:

1. An electrical motive power system 95 wherein the current for driving a motor vehicle is derived by trolley shoe contact with a third rail, characterized by an ice cutter in the form of a wheel having a flat lower side adapted to slide on said rail, having its pe- 100

riphery provided with cutting teeth to cut the ice off the rail, mounted on the vehicle to rotate about a vertically disposed axis in front of the trolley shoe, with an electric motor in axial alinement with said ice cutter for the operation thereof.

2. A structure as specified in claim 1, said motor forming a support whereby said ice cutter is mounted on the vehicle.

10 3. A structure as specified in claim 1, said motor forming a support whereby said ice cutter is mounted on the vehicle, with a yielding spring cushion connection between said motor and ice cutter, serving to press the flat lower side of the cutter against the top of the rail.

15 4. A structure as specified in claim 1, said motor forming a support whereby said ice cutter is mounted on the vehicle, with spring means and a horizontal pivot for said motor, whereby to automatically tilt the forward edge of the cutter upward while crossing a gap in the third rail.

20 5. A structure as specified in claim 1, said motor forming a support whereby said ice cutter is mounted on the vehicle, with spring means and a horizontal pivot for said motor, whereby to automatically tilt the forward edge of the cutter upward while crossing a gap in the third rail, with spring means on said axis to cushion the downward pressure of the cutter on the rail.

25 Specification signed this 16th day of May, 1930.
